UNITED STATES PATENT OFFICE.

THEODOR WILLMA, OF MILWAUKEE, WISCONSIN, ASSIGNOR OF ONE-FOURTH TO CARL RUNGE, ONE-EIGHTH TO MARTIN WOLSKI, AND ONE-EIGHTH TO STANISLAW KIELAR, ALL OF MILWAUKEE, WISCONSIN.

CRUSHER.

1,009,004.

Specification of Letters Patent. Patented Nov. 14, 1911.

Application filed February 16, 1911. Serial No. 608,952.

To all whom it may concern:

Be it known that I, THEODOR WILLMA, a citizen of the United States, and resident of Milwaukee, in the county of Milwaukee and State of Wisconsin, have invented certain new and useful Improvements in Crushers; and I do hereby declare that the following is a full, clear, and exact description thereof.

10 My invention consists in what is herein particularly set forth with reference to the accompanying drawings and pointed out in the claims of this specification, its object being to provide for simple, economical and 15 effective secondary crushing of material in an apparatus designed for the separation of mineral from other substances.

Figures 1 and 2 of the drawings represent sectional views of a separator in which my 20 improvements are embodied, these views being respectively indicated by lines 1—1 and 2—2 in the next described figure; Fig. 3, represents a plan view of the separator having a crushing-block of the same removed; 25 Fig. 4, an elevation of a fragment of the machine partly in section; Fig. 5, a similar view, the section being indicated by line 5—5 in Fig. 3; Fig. 6, a detail plan view of a distributer-plate in the machine, and Fig. 30 7, a cross-section of a spray-trough in said machine.

The framework of the separator is of any suitable material and construction according to the nature of said material. The separator embodies a primary crusher comprising a hopper 10 containing a fixed jaw 11 and a pair of rocker jaws 12 each intermediate of the fixed jaw and a wall of the hopper. The bottom of the hopper is a 35 trough for a spiral conveyer 13 by which the crushed material is fed to an elevator 14 that discharges into a union hopper 15 of chutes 15', and a preferably pivotally adjustable partition 16 is arranged in the hopper. Each chute is provided with a discharge control gate 17 at its lower end. The 40 pivotal partition is adjustable to regulate the quantity of material automatically fed to either of the chutes, as may be desirable 45 from time to time in the operation of the machine, and said chutes are disposed so as to discharge into pivotally connected tilt-sections 18 of the bed-box of a secondary crusher, that embodies a rocker-block 19

having segmental lower side racks 20 engaging horizontal racks 21 on the frame of the machine. The tilt-sections of the aforesaid bed-box discharge alternately upon a vibratory screen 22, and the tailings from this screen have gravity descent along a 55 suitably arranged conductor 23 to the elevator hopper 14' to be fed back to the secondary crusher. The fine material that passes through the screen 22 falls into a receptacle 24 and is mingled with water admitted to said 60 receptacle through a feed-pipe 25 to form a semi-liquid substance that escapes through a nozzle 25' of the aforesaid receptacle onto an inclined distributer plate 26, that in turn 65 discharges onto the first of a plurality of 70 shaking tables 27 on different planes and arranged to feed from one to another, these 75 tables being preferably spirally grooved, the grooves being gradually widened from the receiving end to the discharge end of each 80 table to trap mineral from which other material has been washed away. The outermost table discharges into compartments of a preferably partitioned settling box 28 having upper overflow spouts 28' that empty 85 into a lead-off trough 29, mineral particles being trapped in said settling-box from which the lighter material is washed away by water fed to said tables from spray-troughs 30 suspended over the same, the 90 water being supplied to said troughs through pipes 31.

In practice the movable parts of the machine are actuated by any suitable means, but a convenient operating mechanism is 95 shown and now described as follows: The frame of the machine is provided with bearings for a series of shafts. One shaft 32 is fast in a pulley 33 for a drive-belt 34, and a gear-wheel 35 combined with this pulley 95 meshes with a pinion 36 fast on a shaft 37 provided with a cam-wheel 38 engaged by an arm 22' of the screen 22 that has pivotal connection with a support 39 with which said frame is provided. The shaft 100 37 is connected by a belt 40 and pulleys 40' with a shaft 41, that in turn is connected by a belt 42 and pulleys 42' with a crank-shaft 43 connected by a link 44 with a roller-supported grid 45, whereby reciprocative 105 motion is imparted to said grid. The crank-shaft 43 is provided with a cam-wheel 46 engaged by an arm 27' of one of the tables

27 that has pivotal connection with the aforesaid grid, and roller support thereon. Hence it will be observed that the table has compound reciprocating and vibratory motion. The other table 27 also shown is 5 roller-supported on a grid similar to the one aforesaid to which it is pivotally connected. The outermost grid is roller-supported and the two grids as well as the two tables being 10 coupled they have the same reciprocative and vibratory motion. The grids and tables may be indefinitely continued in the manner aforesaid.

The shaft 32 carries spur-wheels 47 in 15 mesh with similar wheels 48 on a counter-shaft 49, and pitman 50 wristed to the counter-shaft spur-wheels connect with slides 51 to which the rocker-jaws 12 of the primary crusher are joined by pins 52 that 20 extend through horizontal slots 53 in the sides of the hopper 10.

The main shaft 54 of the machine carries 25 a pulley 55 driven by a power-belt 56, and another pulley 57 on the same shaft drives the belt 34. Another belt 58 driven from 30 the shaft 54 is trained on an idler 59, an elevator-shaft pulley 60, another idler 61 and a pulley 62 on the shaft 32. The power-shaft is also provided with a spur-pinion 63 35 in mesh with a spur-wheel 64 wristed to a pitman 65 that connects with the rocker block 19 of the secondary crusher, this block being one of great weight in order to effectually crush the material fed to the bed-box 35 of said crusher.

The rocker-block 19 is provided with bearing-brackets 66 for rods 67 to which paired depending plural-hook grabs 68 are connected, one grab of each pair being in the 40 form of a bell-crank having an arm 68' thereof coupled to a spring 69 attached to said block, that is provided with stops 69' in opposition to the grabs. A link 70 connects the arm with a lever 71 fulcrumed on 45 the rocker-block and arranged to be actuated against the resistance of the spring 69 by a double cam-plate 72 attached to the framing of the machine.

When the block 19 is on rock in either direction, the upper hooks of a pair of the 50 grabs first engage lateral pins 73 of one of the bed-box sections 18 to lift the same to a predetermined inclination said grabs being disengaged from the pins by a lift of the 55 companion lever 71 on one prong of the opposing cam-plate 72 to permit a drop of said bed-box section to normal position, whereby the previously crushed material therein is loosened. Upon continued rock of the block 60 19 in the same direction there is engagement of the lower hooks of the aforesaid grabs with the pins of the aforesaid bed-box section to lift the same to a dumping inclination its contents being discharged onto the 65 screen 22. By the time this operation has

been effected the other prong of the aforesaid cam-plate will have actuated the aforesaid lever to release said bed-box section and permit its return to normal position.

Each chute gate 17 is shown provided 70 with a lateral pin 73 over a lever 74 fulcrumed upon a support 75 for the chute and connected by a link 76 with another lever 77 fulcrumed on the same support. The lever 77 being in the path of a lateral pin 78 of 75 the rocker-block 19, the gate 17 is lifted subsequent to the second return of the adjacent tilt-section of the aforesaid bed-box to discharge material to the secondary crusher, a swing-spout 79 of the aforesaid chute being linked to said gate to be lifted into working position.

The distributor-plate 26 is triangular in plan and provided with suitably arranged projections 26' by which to scatter the flowing 85 material.

Each spray-trough 30 herein shown has divergent and serrated sides and flanges, the serrations of the flanges breaking joints with those of the sides to facilitate the spraying 90 from said trough.

I claim:

1. The combination of a two section bed-box, a rocker-block engaging the box, chutes by which to deliver material to the box-sections, gates controlling the discharge ends of the chutes, means for dumping the bed-box sections alternately, and means for opening each chute-gate coincident with a return of an adjacent bed-box section to normal 100 position subsequent to a dumping operation.

2. The combination of a two-section bed-box, a rocker-block engaging the box, spring-and-cam controlled plural hook grabs in connection with the block and engageable with 105 projections of the box sections to trip-lift the same to different inclinations from normal position, gated chutes by which to deliver material to said box-sections, and block-controlled means for opening each 110 chute-gate coincident with the return of an adjacent bed-box section to normal position after lift of the same to the greatest or dumping inclination.

3. The combination of a two-section bed-box, a rocker-block engaging the box, spring-and-cam controlled plural hook grabs in connection with the block and engageable with projections of the box-sections to trip-lift the same to different inclinations 115 from normal position, gated chutes by which to deliver material to said box-sections, block-controlled means for opening each chute-gate coincident with the return of an adjacent bed-box section to normal 120 position after lift of the same to the greatest or dumping inclination, and a gate-controlled swing-spout in connection with each chute.

4. The combination of a two section bed- 130

box, a block engaging the box and provided with segmental side racks, horizontal racks engaged by the racks aforesaid, means for feeding material to the box-sections, means 5 for actuating the block, and means for dumping said box-sections alternately.

In testimony that I claim the foregoing I

have hereunto set my hand at Milwaukee in the county of Milwaukee and State of Wisconsin in the presence of two witnesses. 10

THEODOR WILLMA.
